UNITED STATES PATENT OFFICE.

HENRY G. VOIGHT AND CHARLES J. CALEY, OF NEW BRITAIN, CONNECTICUT, ASSIGNEES
TO RUSSELL & ERWIN MANUFACTURING COMPANY, OF NEW BRITAIN, CONNECTICUT,
A CORPORATION OF CONNECTICUT.

LOCK CONSTRUCTION.

No. 897,802.

Specification of Letters Patent.

Patented Sept. 1, 1908.

Application filed March 18, 1908. Serial No. 421,928.

To all whom it may concern:

Be it known that we, HENRY G. VOIGHT and CHARLES J. CALEY, citizens of the United States, residing at New Britain, county of 5 Hartford, State of Connecticut, have invented certain new and useful Improvements in Lock Construction, of which the following is a full, clear, and exact description.

Our invention relates to improvements in 10 locks, and has for its object means for connecting a lock to a door in a simple and efficient manner.

In the drawings, Figure 1 is a front elevation of an escutcheon plate member of the 15 lock, certain parts being removed. Fig. 2 is a vertical section, a certain part being shown in elevation. Figs. 3 and 4 are views corresponding respectively to Figs. 1 and 2, but showing a modification.

20 1 represents the stile of a door to which the lock is to be applied.

2 is the case of a lock of the well-known "rim lock" type.

25 2^a is the rear cover or cap-plate which is secured to the case 2 after the lock mechanism (not shown) is placed therein, the said plate being secured in any well-known manner, as by ordinary machine screws (not shown). Projecting rearwardly from the 30 cap-plate 2^a is a hollow tubular boss 2^b. In the drawings two of these tubular bosses 2^b are shown. Where these bosses 2^b meet the cap-plate 2^a there is a somewhat reduced threaded portion 2^c arranged to receive the 35 threaded end of a cylinder lock 3, so that the roll-back 3^a thereof will stand within the case 2 to properly engage the lock mechanism, in the well-known manner.

40 4 is an escutcheon plate adapted to the opposite side of the door from the case 2. The tubular extension 2^b is adapted to extend through a passage in the door stile near and through a passage in the escutcheon plate 4, the outer end of said tubular extension being threaded to receive a clamping 45 nut 5.

45 6 is a rose plate or finishing plate adapted to bear against the escutcheon plate 4 and overstand the nut 5, hiding the latter from view when the parts are assembled. The cylinder lock 3 serves to hold the finishing plate 6 against its seat, the flanged outer end

of said lock 3 holding said finishing plate 6 in place, as shown in Fig. 2.

The usual set-screw (not shown) carried by 55 the case 2 and arranged to engage in a side groove of the cylinder lock, in the usual manner, retains it in place after proper adjustment has been effected.

As will be seen, by this arrangement an 60 absolutely accurate alinement of the parts may be effected, and at the same time the case 2, plate 4 and finishing plate 6 may be 65 properly positioned and firmly clamped together, the only manner of separating said parts being possible while the door stands open and access may be had to the means for holding the cylinder lock against removal.

It should be understood that the escutcheon 70 plate may be of any desired shape or design, in this instance its most important function being to furnish a proper bearing for the locking device 5. The tubular boss affords not only a broad bearing support and connection, but also provides a passage whereby 75 access may be had to the interior of the lock from the outside through the medium of a proper instrumentality, for example, such as a key adapted to the cylinder lock 3. Where a cylinder lock is employed, it, in turn, serves 80 to reinforce the strength of the tubular boss 2^b, for, as will be apparent, it would not only be necessary to tear away the locking device 5 before the escutcheon could be removed and the lock released, but it would also be 85 necessary to break the connection of the cylinder lock 3 with the cap-plate 2^a, which would be practically impossible and an act that would not be resorted to in view of the many easier methods of obtaining an unlaw- 90 ful entry.

In Figs. 3 and 4, we have shown a modification in which, instead of extending the tubular boss entirely through the door, it is extended partially through the same, in this instance a companion tubular boss being formed on the rear of the escutcheon plate. The bosses in this case are flanged inwardly to provide a bearing for clamping devices in the form of screws to take the place of the 100 clamping nut 5. In this instance, as before, the protecting rose may be employed but, as shown, may be of a different form. In Figs. 3 and 4, 1 represents the door stile, 2 the lock

case and 3 the cylinder lock, as before. 2^e is the cap-plate, 2^f is the inwardly extending tubular boss from the cap-plate 2^e, said boss being provided with an inwardly directed flange 2^g. 4^a is the escutcheon plate, 4^b is a tubular boss projecting rearwardly therefrom and corresponding to the boss 2^f. 4^c is a flange on the boss 4^b corresponding to the flange 2^g. These flanges afford clearance 10 room for the securing screws 5^a to draw said bosses toward each other to clamp the lock case 2 and escutcheon 4^a tightly against opposite sides of the door. In this instance the screw-thread to receive the threaded end of 15 the cylinder lock 3 may be formed at the inner edge of the flange 2^g. 6^a is the rose-plate overstanding the cavity within the boss 4^b, as best seen in Fig. 4. In this instance, as before, the protecting rose 6^a is held in proper position by the flange at the 20 outer end of the cylinder lock 3.

The lock case on one side constitutes one member and the escutcheon another member to be clamped to the door, and in the claims 25 we will use these terms in order to give the proper scope thereto.

What we claim is:

1. In a device of the character described, an outside member, an inside member, a 30 threaded annular boss carried by and projecting to the rear of one of said members, a coupling device carried by the other member arranged to operatively engage the end of said boss, said boss having a passage, and a lock mechanism detachably mounted therein.

2. In a device of the character described, an inside member, a separate outside member, a tubular boss projecting from one of said members through the other member, 40 and a separate clamping means arranged externally of the last mentioned member co-operating with said boss.

3. In a device of the character described, an inside member, an outside member, a 45 tubular boss projecting from one of said members through the other member, a clamping means arranged externally of the other member co-operating with said boss, a guard for said clamping means, and means 50 to hold said guard in place.

4. In a device of the character described, an inside member, an outside member, a tubular boss projecting from one of said members through the other member, a 55 clamping means arranged externally of the other member co-operating with said boss, a guard for said clamping means, means to hold said guard in place, and a device carried by the first mentioned member to lock the 60 last mentioned means against disengagement.

5. In a device of the character described, two members to be connected, a threaded tubular boss being carried by one of said members and projecting toward the other

member, and a clamping device carried by 65 the latter and arranged to engage said tubular boss to clamp said members on opposite sides of the door, and means carried by the last mentioned member to cover and protect 70 said clamping device.

6. In a device of the character described, two members to be connected, a tubular boss carried by one of said members and projecting toward and through the other member, the extremity of said tubular boss being externally threaded, a correspondingly threaded clamping member arranged to contact with said tubular boss to draw said members toward each other, and a protecting device arranged to cover and hide said clamping 80 device.

7. In a device of the character described, two members to be connected, a threaded tubular boss carried by one of said members and projecting toward and through the other 85 member, the extremity of said tubular boss being threaded, a correspondingly threaded clamping member arranged to coact with said tubular boss to draw said members toward each other, a protecting device arranged to cover and hide said clamping device, and a lock actuating mechanism passing through said tubular boss and accessible at 90 one side of the door.

8. In a lock mechanism, a lock case, an 95 integral tubular boss extending to the rear thereof, an escutcheon plate arranged to bear against the opposite side of the door from the lock case, said tubular boss passing therethrough, a securing device coöperating 100 with the free extremity of said tubular boss and the escutcheon plate, and a detachable protecting device for said locking device.

9. In a lock mechanism, a lock case, a 105 tubular boss extending to the rear thereof, an escutcheon plate arranged to bear against the opposite side of the door from the lock case, said tubular boss passing therethrough, a securing device coöperating with the extremity of said tubular boss outside of the 110 escutcheon plate and the protecting device for said locking device, and a cylinder lock passing through said tubular boss and holding 115 said protecting device in place.

10. In a lock mechanism, a lock case, a 115 tubular boss extending to the rear thereof, an escutcheon plate arranged to bear against the opposite side of the door from the lock case, said tubular boss passing therethrough, a securing device coöperating with the extremity of said tubular boss, a cylinder lock 120 passing through said tubular extension and holding said protecting device in place, and a threaded passage within said boss to receive such cylinder lock.

11. In a door lock, a lock adapted to be secured to the inside of the door, an escutcheon plate adapted to be secured to the

outside of the door, a tubular boss carried by the lock and projecting rearwardly therefrom toward the escutcheon plate, a clamping device carried by a part of the escutcheon plate and coöperating with said tubular boss, said clamping device being accessible for operation from the outside of the door when the lock is applied, and a protecting guard

arranged to conceal and protect said clamping device.
